UNITED STATES PATENT OFFICE.

JAMES W. RUMSEY, OF SUISUN, CALIFORNIA.

CAR-DOOR.

No. 911,617.

Specification of Letters Patent.

Patented Feb. 9, 1909.

Application filed March 28, 1908. Serial No. 423,853.

To all whom it may concern:

Be it known that I, JAMES W. RUMSEY, citizen of the United States, residing at Suisun, in the county of Solano and State of California, have invented new and useful Improvements in Car-Doors, of which the following is a specification.

My invention relates to improvements in car doors, and is especially designed for the 10 class of doors used upon freight cars.

It consists in the combination of parts, and in details of construction which will be more fully explained by reference to the accompanying drawings, in which—

15. Figure 1 is a front view. Fig. 2 is a vertical section.

In the usual construction of such doors, a timber frame-work is made, and the boards forming the door are secured upon this 20 frame-work, leaving the timbers on the interior exposed so that if boxes or goods happen to fall against them, they will often prevent the opening of the doors. Such doors as ordinarily constructed are liable to 25 bind so as not to be readily opened when they are pushed for the purpose of sliding them, when opening; and lastly, in the ordinary construction of doors, very considerable spaces appear through which dust 30 and dirt, and sometimes sparks may enter the car, to the great damage of delicate goods that may be contained therein.

It is the object of my invention to overcome these difficulties, and to provide a door 35 that is smooth on both surfaces, to properly hang and balance the door so that it will always run easily in opening and closing, and to provide such closures as will prevent the entrance of dust into the car.

40. In the drawings, I have only shown so much of the car and connected parts as will enable me to explain my invention.

A shows the side of the car, and B represents a portion of the car floor.

45. The door is made of sufficiently heavy diagonally placed strips 2 which are closely jointed together and form the inner face. Upon this inner structure are secured the vertical boards 3, the whole being strongly 50 secured together; and forming a door which is smooth upon both sides.

To the side of the car above the door opening is fixed a metal trough 4, and in the upper part of this trough is fixed a strip of wood 5

running the length of the trough; the strip 55 of wood and the trough being bolted together and to the car.

The bottom is formed by bending the sides at right angles, and these form a support for the rollers, with a channel between for the 60 passage of the hanger hereafter described.

6 are rollers mounted upon axles 7 which are fixed in hangers 8. These hangers extend downwardly through the above mentioned slot, and may be let into the material 65 of the doors substantially central between the outer and inner sides thereof, and they are firmly bolted or otherwise secured thereto, as shown at 9. This construction causes the door to be evenly balanced, and the 70 rollers travel upon the inturned flanges of the trough.

4^a is a sheet of rolled steel bolted on the outside of the trough and extending down outside the door to cover the space between 75 the upper edge of the door and the trough to prevent the entrance of dust, rain or sparks. The door closes flush against the door-frame 13.

10 is an angle iron trough bolted to the 80 side of the car just below the floor, and the inner portion 2 of the door extends downwardly into this trough as shown.

11 is a strip of half round iron which is fixed on the outside of this extended portion 85 of the door; and if any pressure be brought upon the door from the inside, this strip will be pressed against the inner portion of the trough 10, making a comparatively 90 small bearing, and allowing the door to be moved more easily.

The outer part 3 of the door extends down to just above the top of the trough 10, and it projects sufficiently beyond the edge 95 of the trough to divert any water from rains or otherwise, and discharge it outside the trough.

12 is a strip of iron fastened to the edge of the door, extending the full length thereof, and its lower end is bent to an angle as 100 shown, so that when the door is closed, it overlaps the lower end of the trough and door-frame, and prevents dust, water or sparks from entering.

A door constructed in this manner may be 105 easily opened and closed, since it is not subject to being locked from the pressure of boxes against the inside; the smooth surface

allowing it to be moved without the use of crowbars or other means for forcible entry. Such a door will last for many years with few repairs. The manner in which the door 5 is hung, coupled with the wheels and trough upon which it rolls, is also a special feature; the trough having sufficient clearance to allow the door to roll easily; and if by pushing against the door, it should be pushed 10 upwardly or diagonally, the rollers will strike the top of the trough, making it impossible to bind in this manner. Hoods, such as are used with doors of this class, are unnecessary as the trough, itself, forms a 15 hood. The troughs, top and bottom, form practically seals to prevent dust from entering the car, and the bottom trough forming a guide for the door, will prevent its flying out so as to strike cars on sidings, or passing 20 on other tracks.

Having thus described my invention, what I claim and desire to secure by Letters Patent is—

1. The combination in a car having a side 25 door opening, of a rectangular channel iron trough with inturned lower edges fixed horizontally above the door opening, and having an exterior downwardly extending lip, a corresponding trough with upturned flange 30 fixed below the door opening, a door formed of transversely secured boards, the interior layer of which extends below the exterior layer and the car floor, and enters the lower

trough, and the upper edge of the door extending within the upper lip, hangers 35 fixed centrally between the door layers, and extending upwardly into the upper trough, wheel shafts fixed transversely to the hangers, and wheels journaled thereon on each side of the hangers, and supported on the 40 inturned flanges of the trough.

2. In a car door opening closure of the character described, a smooth-surfaced double layer door, with hangers fixed centrally between the layers, a horizontal rectangular open-bottomed trough fixed above the door-opening having a depending lip, into which trough the hangers project, wheels journaled on opposite sides of the hangers, and supported on the trough bottom, an 45 50 angular open top trough fixed below the door opening, into which the lower interior layer of the door extends, and which the exterior overlaps, and a strip of iron fixed to the vertical edge of the door, and having an 55 angular bend at the bottom to engage and overlap the end of the trough when the door is closed.

In testimony whereof I have hereunto set my hand in presence of two subscribing 60 witnesses.

JAMES W. RUMSEY.
